(Cl. D44—26)

To all whom it may concern:

Be it known that we, Richard V. Smith and Jack Kauffman, citizens of the United States and residing at Glendale, in the county of Los Angeles, State of California, and Los Angeles, county of Los Angeles, State of California, respectively, have invented a new, original, and ornamental Design for a Holder for Condiment Containers, of which the following is a specification, reference being had to the accompanying drawing, forming part thereof, in which:

Fig. 1 is a top plan view of a holder for condiment containers showing our new design,

Fig. 2 is a side elevation thereof, and

Fig. 3 is a bottom plan view of the holder shown in Figs. 1 and 2.

We claim:

The ornamental design for a holder for condiment containers, substantially as shown.

JACK KAUFFMAN.

RICHARD V. SMITH.
